UNITED STATES PATENT OFFICE.

PHILIP C. P. BOOTY, OF CHICAGO, ILLINOIS, ASSIGNOR, BY MESNE ASSIGNMENTS, TO
LESLIE W. FRICK, OF OAK PARK, ILLINOIS.

ARTICLE OF MANUFACTURE.

Application filed December 20, 1923. Serial No. 681,737.

To all whom it may concern:

Be it known that I, PHILIP C. P. Booty, a subject of the King of Great Britain, residing at Chicago, in the county of Cook and 5 State of Illinois, have invented certain new and useful Improvements in Articles of Manufacture, of which the following is a specification.

My invention relates to a new article of 10 manufacture and more particularly to a novel container adapted to be filled with a compressed compound of such ingredients as are commonly used in loose powder form for application to the face, or for polishing the 15 nails, etc.

The use of face powders, nail polishes, and the like in loose form is objectionable because they are bulky, unsanitary to use and inconvenient and messy to carry. As ordinarily prepared in cake or compact form, 20 binders are used for such compounds which are objectionable because when a binder is used in the face powder it tends to irritate the skin, and when a binder is used in a nail 25 polish it tends to destroy the effectiveness of the polish. I have discovered that the ordinary loose compounds of face powders, nail polishes, and the like can be compressed into agglomerate masses without the use of binders; but such masses, however, disintegrate 30 easily and require a suitable container. It is one of the objects of my invention to provide a container for such a compressed compound of such construction that it will effectively hold the compressed compound 35 when not being used while the walls thereof may be removed gradually whereby the compressed compound may be gradually uncovered 40 or exposed so that it may be rubbed off as it is needed for use.

A further object of my invention is the provision of a container for such compressed compounds of very simple construction, inexpensive to manufacture and which will 45 be well adapted for the purpose.

The invention consists in the novel constructions, arrangements and devices to be hereinafter described and claimed for carrying out the above stated objects and such other objects as will appear from the following description of certain preferred embodiments illustrated in the accompanying drawing, wherein—

Fig. 1 is a perspective view of an empty

container embodying certain principles of 55 my invention;

Fig. 2 is a sectional view of the container shown in Fig. 1 filled with a compressed compound; and

Fig. 3 is a sectional view of a modified 60 form of container made according to my invention and filled with a compressed compound.

Referring first to Figs. 1 and 2, the container illustrated therein, designated generally by the reference character 6, comprises a cord 7 of any suitable material, for example, cotton or linen, which is arranged in the form of a coil, the convolutions 8 of which are superposed and are held in said 70 relation by any suitable means, for example, by the application of a thin coat of some suitable cementitious agent to the outer or inner surface of the coil. The compound 75 may be introduced into the container loosely and compressed in the container, in which case, the container is supported, while the compound is being compressed, by being slipped into a suitable support or die. I prefer, however, by the use of suitable means 80 to compress the compound into an agglomerate mass 9 of such shape and size that it will slip into the container. A cementitious agent 10 may be applied either to the outside of the compressed compound or to the 85 inside of the container to prevent slippage of the one relative to the other. A disk 11 of paper or the like may be inserted as a bottom for the container, said disk being held in place either frictionally or by an 90 adhesive.

In that form of my invention shown in Fig. 3, the container comprises a plurality of thin apertured disks 12 of any suitable material, for example, paper, which are arranged in superposed relation. A cord 13 is coiled so that its convolutions surround the superposed disks. The disks 12 and the convolutions of the cord 13 may be held in the desired relation by any suitable means, for 100 example, by a cementitious agent applied to the convolutions of the coil, sufficient of the agent working between the convolutions of the coil and onto the peripheries of the disks to bind the latter together. The disk 105 14 is not perforated and forms the bottom of the container. The compound may be introduced either loosely into this container

and compressed therein or it may be first compressed into an agglomerate mass 15 of the proper size and shape and slipped into the container. In the latter case the mass 5 is preferably held in the container by a suitable cementitious agent 16 applied either to the inner surface of the container or the outer surface of the mass.

In each form of my invention it will be 10 noted that the wall of the container may be gradually removed to expose gradually the compressed compound as it is needed for use. In the form of my invention shown in Figs. 1 and 2 the upper end of the cord 7. 15 is simply pulled sufficiently to remove one or two of its convolutions, the uncoiled portion of the cord being then cut off. Uncoiling the cord exposes the compressed compound so that it may be rubbed off onto a 20 piece of chamois, or the like, for application to the skin or the nails, as may be desired. In that form of my invention shown in Fig. 3 one or two convolutions of the cord are uncoiled and cut off and then sufficient 25 of the top disks are removed to expose the compressed compound so that it may be rubbed away.

The containers shown in the drawings are 30 cylindrical in form as it is more practical to make them and to compress the compound in that form. It will be obvious, however, that the containers may be made and the compound compressed in other forms or shapes, for example, rectangular or oval.

35 The containers are inexpensive to manufacture, attractive in appearance and small in size. A compound put up in the manner herein described occupies much less space than when packed loosely in a box and hence 40 it is more convenient to carry. The compressed compound does not come out of the container or rub away unless a portion of the container wall is purposely removed, therefore, the compound does not spill. The

containers filled with a suitable nail polish 45 compound are particularly useful for the professional manicurist in connection with the manicuring implement described and claimed in my co-pending application Serial No. 576,485 filed July 21, 1922, wherein a 50 fresh unsoiled polishing strip is used for each person. In the use mentioned the compound is only rubbed on an unsoiled or un-used strip and, therefore, a strictly sanitary manicure is the result, there being, in that 55 case, no opportunity for infectious germs to be transferred from one person to another.

I do not intend to limit my invention to the details of construction shown and described, except only in so far as certain of 60 the appended claims are specifically so limited, as it will be obvious that modifications may be made without departing from the principles of my invention.

I claim:

1. A container formed of a series of convolutions of cord arranged in contact with each other in a single layer and held together by a cementitious agent.
2. A toilet article, comprising a compound 70 held together by compression in the form of a stick, and a series of convolutions of cord arranged about said stick in contact with each other in a single layer, the convolutions of cord being held in contact with each other 75 and in contact with the stick by a cementitious agent.
3. A nail polishing device, comprising a compound of abrasive and polishing materials held together by compression in the 80 form of a stick, and a series of convolutions of cord arranged about said stick in contact with each other in a single layer, the convolutions of cord being held in contact with each other and in contact with the stick by 85 a cementitious agent.

PHILIP C. P. BOOTY.

Certificate of Correction.

It is hereby certified that the name of the assignee in Letters Patent No. 1,582,242, granted April 27, 1926, upon the application of Philip C. P. Booty, of Chicago, Illinois, for an improvement in "Articles of Manufacture," was erroneously written and printed as "Leslie W. Frick," whereas said name should have been written and printed as *Leslie W. Fricke*, as shown by the records of assignments in this office; and that the said Letters Patent should be read with this correction therein that the same may conform to the record of the case in the Patent Office.

Signed and sealed this 1st day of June, A. D. 1926.

[SEAL.]

M. J. MOORE,
Acting Commissioner of Patents.
